UNITED STATES PATENT OFFICE

2,567,271

APPARATUS FOR HANDLING ROD AND WIRE BUNDLES OR THE LIKE

Bruce N. Bletso, Cleveland Heights, Ohio, assignor to The American Steel and Wire Company of New Jersey, a corporation of New Jersey

Application February 28, 1950, Serial No. 146,783

4 Claims. (Cl. 193—40)

1

The present invention relates to rod and wire handling mechanism and more particularly to apparatus used in conjunction with a feeding device for wire processing machinery for furnishing an uninterrupted supply of bundles of rod or wire to the feeding device so as to permit continuous operation of the wire processing machinery.

In the fabrication of rod and wire products it is necessary to maintain the rod or wire being processed in a continuous unbroken strand as it enters processing equipment such as wire drawing machines, nail forming machines, etc., for efficient operation. Since rod and wire are normally supplied in bundles or coils, it is necessary to provide means whereby the bundles may be so positioned before the wire-working machine that as each individual bundle is exhausted another is in position to continue the feeding without interruption.

Various types of apparatus had been used for this purpose prior to my invention but none had proven entirely satisfactory. The most simple of these consisted of a hair pin hook loaded with three or four bundles of rod or wire suspended by a crane before the entry end of the wire-working machine. This type was unsatisfactory due to the limited capacity of the hook. The most common type of pay-off machine in use heretofore consisted of a double or triple arm rotary flipper reel. In operation thereof a bundle of rod or wire was loaded on each arm of the machine and one arm was positioned before the entry end of the wire-working machine. The bundles were connected to each other by welding their ends together so that as each bundle was exhausted the operator maintained continuous operation by rotating the arms 120° or 180° to move another bundle to feeding position. He then loaded another bundle on the empty arm and welded its front end to the rear end of the bundle next to it. The arms of the mechanism consisted of an upper and lower branch and were each provided with a flipper mechanism that restricted the unreeling of the bundles to single convolutions in consecutive order. A typical machine of this sort is described by G. H. Rose in his U. S. Patent No. 2,263,889.

One of the serious disadvantages inherent in this machine was the difficulty encountered when loading the arms. Each time the operator loaded an arm it was necessary for him to hold the two branches of the arm together while manually pushing the bundle thereon. This required considerable dexterity on the part of the operator

2

to perform the job safely. It was also necessary for him to exert considerable force when rotating the arms of the apparatus from one position to another when loaded with the bundles which weigh up to 300 pounds each.

It is accordingly an object of my present invention to provide a rod and wire handling apparatus for supporting a plurality of bundles of rod or wire and for advancing the bundles in uninterrupted sequential order to a pay-off mechanism feeding a wire processing machine.

It is another object of my invention to provide a rod and wire handling apparatus for wire-working machines which is inexpensive to construct, rugged in structure and which requires a minimum of manual manipulation for operation.

These and other objects will be more apparent after referring to the following specification and attached drawings, in which:

Figure 1 is a plan view;

Figure 2 is a side elevation;

Figure 3 is a sectional view taken on the line III—III of Figure 2;

Figure 4 is an enlarged sectional view taken on the line IV—IV of Figure 1;

Figure 5 is an enlarged sectional view taken on the line V—V of Figure 4;

Figure 6 is a schematic illustration of the several phases in the operating cycle of the invention; and

Figure 7 is a side elevational view showing a modification in the mounting of the invention.

Referring more particularly to the drawings, reference numerals 2 and 4 indicate two C-shaped bevel ring or segmental gears which are disposed in juxtaposition and rotatively confined by two pairs of guiding brackets 6 and 8. The two pairs of brackets are arranged in spaced relation, one above the other, as most clearly seen in Figure 3. The gears are so positioned that they may be rotated in opposite directions to bring the open spaces between the ends of the gears in registry first on one side and then on the other as will be more fully described hereinafter.

The gears 2 and 4 are provided with teeth 10 and 12, respectively, on their adjacent faces. The gears are driven by a bevel pinion 14 which is disposed between the gears and meshes with the teeth 10 and 12 to drive one gear in a clockwise direction and the other in the counter-clockwise direction. Pinion 14 normally meshes with both gears except when the open space in one or the other gear passes the pinion. The gears are so positioned, however, that the pinion 14 is always

in mesh with one or the other of the gears. Pinion 14 is connected with and is driven by a suitable power source such as a geared motor 16.

An elongated skid 18, which extends from both sides of the gears 2 and 4, is supported and carried by the lower pair of guiding brackets 8 by means of bolts 20 which attach the skid 18 to the guiding brackets 8, as seen in Figure 4. A roof portion 19 joins the two sides of the skid. Openings 21 and 23 are provided in the roof portion 19 to permit the gears 2 and 4 to pass therethrough during rotation. The skid 18 slopes slightly from its loading end 22 towards its discharge end 24. A flipper mechanism or feeding device 25 for paying-off the rod or wire from the bundle to the wire-working machine is mounted on the discharge end of skid 18. The flipper mechanism shown in Figures 1 and 2 is similar to and functions in the same manner as the apparatus shown by Rose in the above-mentioned U. S. Patent No. 2,263,889 and is not claimed as part of my invention. The top pair of guiding brackets 6 is mounted by means of bolts 26 to an overhanging support member 28. The support member 28 may be suspended from any suitable supporting structure, such as the beams 29 shown in Figure 2.

Two pairs of spaced bevel idler pinions 30 and 32 are mounted between the inner toothed faces of the gears 2 and 4 and mesh with the teeth 10 and 12. Pinions 30 and 32 are not connected to an outside power source but are driven by the gears themselves. The bevel pinions 30 are each mounted on a shaft 34 having its ends rotatively supported in bearings 36. Bearings 36 are fixedly mounted on the guide bracket 8 by means of bolts 38. Pinions 32 are similarly mounted on shafts 40. Shafts 40 have their ends supported in bearings 42 which are fixedly attached to bracket 6 by means of bolts 44. Bearings 36 and 42 not only support the shafts but also act as spacers between the paired brackets 8 and the paired brackets 6, respectively. The paired pinions are so spaced around the circumference of gears 2 and 4 that at least two of the pinions besides the main driving pinion 14 are always in mesh with the teeth 10 and 12 notwithstanding the position of the gears relative to each other. Thus, when the open segment of one gear is opposite the pinion 14 the gear will continue to be rotated by at least two of the paired idler pinions 30 and 32. The idler pinions also act as a differential arrangement which stabilizes the position of the support 28 and the skid 18 keeping each in a fixed relation to the other.

In operation, a plurality of bundles of rod or wire W is placed upon the loading end 22 of skid 18 which end is to the left of the gears 2 and 4 as viewed in Figure 6. These bundles are welded together end-to-end by the operator as they are loaded. The gears are initially in the position A of the operating cycle shown in Figure 6. In order to move the wire to the discharge end 24 of the skid 18 the operator starts motor 16 to rotate pinion 14 and turn the gears 2 and 4 from position A, as shown in Figure 6, through position B to position C of the operating cycle. This causes the open spaces of both gears to be in registry facing the loading end 22 of the skid. The operator then moves the first bundle adjacent the gears along skid 18 until it rests within the gears as seen in position C of Figure 6. In this position the bundle W is still connected by its welded end to the next adjacent bundle positioned on the loading end of skid 18. Thereafter,

the operator starts the motor 16 again to rotate the gears through position D to position E as shown, so that the open spaces of the gears are in registry facing the discharge end of the skid. The bundle of rod or wire in the gears is then pushed out by the operator and slid along the discharge end of the skid on to the arbor bars 46 and 48 of the flipper mechanism 25. During this movement from the one side of the gears to the discharge end of the skid 18, the bundle remains connected by its welded end with the rod or wire still resting on the loading end 22 of the skid. The rod or wire is fed into the wire-working machine from the arbor bars 46 and 48 in the conventional manner. The operator repeats the above described operation each time it is desired to replenish the supply of wire or rod on the arbor bars 46 and 48.

Additional bundles of rods or wire may be placed on the entry end 22 of skid 18 at any time without stopping the flow of wire to the flipper mechanism and to the wire-working machine.

Thus it will be apparent that the ring gears 2 and 4 function not only as a support for the skid 18 which is attached to the paired brackets 8 but also as a gate or lock to permit the unobstructed movement of the bundles of wire or rod along the skid 18 to the flipper mechanism 25.

It will be noted that the apparatus of my invention may be mounted overhead, as I have shown, or it may be floor mounted. As shown in Figure 7, in the latter case pinion 14 is positioned between the lower portions of the gears and the skid 18 is connected to and supported by the upper brackets 6 which confine the upper arc portions of the gears.

While one embodiment of my invention has been shown and described, it will be apparent that other adaptations and modifications may be made without departing from the scope of the following claims.

I claim:

1. Apparatus for handling bundles of rod or wire and the like for use with a pay-off mechanism which comprises a pair of C-shaped ring gears mounted upright in juxtaposition, means for rotating said gears to bring the spaces between the ends in registry in predetermined positions, spaced bracket guide means enclosing an arc portion of said gears, and an elongated skid mounted on said guide bracket means and extending substantially horizontally in both directions therefrom generally in the plane of rotation of said gears.

2. Apparatus for handling bundles of rod or wire and the like for use with a pay-off mechanism which comprises a pair of C-shaped ring gears each having gear teeth on one face thereof mounted upright in juxtaposition with their toothed faces adjacent each other, at least two pairs of spaced guide brackets, said pairs of brackets being spaced vertically to enclose the upper and lower arc portions of said gears, means for rotating said gears to bring the spaces between the ends thereof in registry in predetermined positions, said means including a driven pinion disposed between said gears, said pinion meshing with the teeth on the faces of both gears, means for driving said pinion, and at least one idler pinion disposed between said gears and in mesh with the teeth thereon, said idler pinion being spaced from said driven pinion, and an elongated skid mounted on one of said pairs of guide brackets and extending substantially horizontally in both directions therefrom.

generally in the plane of rotation of said gears.

3. Coil-handling apparatus comprising a skid adapted to have a succession of coils strung thereon and a support for said skid, said support including a pair of C-shaped ring gears disposed in juxtaposition generally in the vertical plane containing said skid, a fixed guide for said gears engaging a portion only of their circumference, said skid being attached to said guide and means for driving said gears to bring the spaces between the ends of the gears in registry first on one side and then on the other whereby coils strung on said skid are permitted to pass along the length thereof.

4. Coil-handling apparatus comprising a skid adapted to have a succession of coils strung thereon and a support for said skid, said support including a pair of C-shaped ring gears each having gear teeth on one face thereof disposed in juxtaposition with their toothed faces adjacent each other and generally in the same vertical plane containing said skid, at least two pairs of fixed guides for said gears, said skid being attached to one of said pairs of guides, said pairs

of guides being spaced vertically to engage the upper and lower portions of the circumference of said gears, and means for driving said gears to bring the spaces between the ends of the gears in registry first on one side and then on the other whereby coils strung on said skid are permitted to pass along the length thereof, said driving means including a driven pinion disposed between said gears, said pinion meshing with the teeth on the faces of both gears, means for driving said pinion, and at least one idler pinion disposed between said gears and in mesh with the teeth thereon, said idler pinion being spaced from said driven pinion.

15 BRUCE N. BLETSO.
